UNITED STATES PATENT OFFICE.

ABRAHAM L. MENZIN, OF SAN FRANCISCO, CALIFORNIA, ASSIGNOR, BY DIRECT AND MESNE ASSIGNMENTS, TO BLAW-KNOX COMPANY, OF BLAWNOX, PENNSYLVANIA, A CORPORATION OF NEW JERSEY.

STEAM TRAP.

Application filed May 10, 1926. Serial No. 107,945.

This invention relates to steam traps for use in connection with steam generating apparatus and particularly in connection with steam separators which are used for purifying the steam of power boilers. One of the objects of the invention is to provide for disposal of condensed steam or other waste water in a more effective manner and so that the size of the apparatus may be materially reduced, or, with similar apparatus, the capacity thereof may be materially increased.

Of the accompanying drawings Fig. 1 is an elevation of a steam separator mounted in a boiler together with a steam trap and the connecting pipes; Fig. 2 is a sectional view along the line 2—2 of Fig. 1; and Fig. 3 is a materially reduced elevation of a separator of several sections mounted in a boiler.

Although my invention applies to the disposal of condensed water or other waste water, with any apparatus where a steam trap or other liquid receiver is used, yet for the purpose of illustrating the invention I prefer to show it as applied to a steam separator and a steam trap to receive the condensate or separated water. The separator 10 is mounted in the usual manner in a boiler 11 and it comprises the banks of baffles 12 which may be of any suitable nature, it being understood that the steam from the boiler passes through the baffles into an outlet 13 of the separator and thence to the steam main 14 outside of the boiler. As the steam passes through the baffles the entrained water flows downwardly on the walls of the vertical baffles into a passageway 15 and thence out of the separator through a pipe 16. Through this pipe the water flows out of the boiler into a pipe 17 and thence into a trap 18 where, by means of a valve 19 operated by a float 20, the water is passed out through a pipe 21 in an ordinary manner. Where a number of sections of separators are used, such as the sections 22, 23, and 24 of Fig. 3, a drain pipe 16 is used for each section and they all connect with a common drain pipe 25. Normally the drain pipes 25 and 17 and the receiver 18 are filled with steam or air. When water begins to flow down the pipes 16 toward the receiver 18 the displaced gas must go somewhere. If there is no vent the gas must flow counter-current to the liquid and thus interfere with the flow of liquid.

To prevent this tendency of the drain pipes

to clog, I provide a vent pipe 26 which projects upwardly into the water chamber 15 of the separator to adjacent the upper wall thereof and is connected, by means of pipes 27 and 28, with the trap, as indicated. In this manner the steam which tends to accumulate in the trap is free to pass out from the trap through the vent pipes back into the water chamber 15 of the separator.

With this arrangement there is no obstruction in the drain pipes owing to any entrained steam or air, and the capacity thereof is very greatly increased, so that the size of these pipes may be very materially decreased for the same separator capacity. At the same time, as the flow of water into the steam trap is continuous and uninterfered with, the flow therein, under normal working operations, is substantially uniform and the tendency is for the valve 19 to be opened more continuously and uniformly, so that the capacities of the trap and the pipe 21 are also very materially increased.

Furthermore, there is no back flow of the entrained steam from the drain pipe into the water chamber of the purifier. Such back flow not only materially disturbs the water in the chamber, but the steam carries with it entrained water. The vent pipe also tends to equalize the pressures in the water chambers when there are several independent sections of separators connected to the same drain pipe, and this much reduces the tendency of local currents of steam or water to flow through the drain pipes and water chambers.

I claim as my invention:

1. The combination of a steam separator and a stationary steam trap, said separator having a steam chamber and a water chamber, and a steam outlet communicating with said steam chamber, a partition separating said chambers, and a drain pipe and a vent pipe continuously operatively connecting said water chamber with said trap, said vent pipe outlet in said water chamber being below said steam outlet.

2. The combination of a steam separator and a stationary steam trap, said separator having a steam chamber and a water chamber, a partition separating said chambers, a drain pipe and a vent pipe continuously operatively connecting said water chamber with said trap, said separator having a dry steam outlet in said steam chamber, and baffles

mounted in said separator between said chambers, the outlet of said vent pipe in said water chamber being below said steam chamber.

5. The combination of a steam separator and a steam trap, said separator having a steam chamber and a water chamber, a partition separating said chambers, and a drain pipe and a vent pipe continuously operatively connecting said water chamber with said trap, the end of said vent pipe projecting into said water chamber to the upper portion thereof.

10. 4. The combination of a boiler, a steam

separator mounted in said boiler, a steam trap mounted outside of said boiler, said separator having a steam inlet and a steam outlet, a water chamber and a steam chamber, two pipes continuously operatively connecting said water chamber with said trap, 20 a partition mounted between said chambers, and steam drying baffles mounted in said separator between said water chamber and said inlet and outlet.

In testimony whereof, I hereunto set my 25 hand.

ABRAHAM L. MENZIN.
